US00D462121S

(12) **United States Design Patent** (10) Patent No.: **US D462,121 S**
 Cartledge et al. (45) Date of Patent: ** *Aug. 27, 2002

(54) **INFUSION PUMP CARTRIDGE**

(75) Inventors: **Richard G. Cartledge, Hugh F. Smisson, III**, both of Macon, GA (US); **Jeffery O. Brown**, North Logan, UT (US)

(73) Assignee: **Smisson-Cartledge Biomedical LLC**, Macon, GA (US)

(*) Notice: This patent is subject to a terminal disclaimer.

(**) Term: **14 Years**

(21) Appl. No.: **29/118,861**

(22) Filed: **Feb. 17, 2000**

(51) LOC (7) Cl. **24-02**

(52) U.S. Cl. **D24/111**
